PRECAST CONCRETE MEMBERS

Albert Henderson, Edgewood, Pa., assignor to
William P. Witherow, Pittsburgh, Pa.

Application September 10, 1945, Serial No. 615,265

11 Claims. (Cl. 72—71)

1

This invention relates to precast building members composed of concrete having reinforcing rods or bars embedded therein and, in particular, to means for connecting a plurality of such members disposed adjacent each other.

This is a continuation-in-part of my application, Serial No. 593,220, filed May 11, 1945. The latter is in part a continuation of my application, Serial No. 480,620, filed March 26, 1943, for Precast concrete building connections which is a continuation-in-part of my prior applications, Serial No. 432,209, filed February 25, 1942, for Precast concrete building, and Serial No. 313,067, filed January 9, 1940, for Concrete building.

Precast concrete building members of various types have been proposed heretofore but, so far as I am aware, no satisfactory provision has been made for rigidly and permanently securing adjacent members together in a building structure. The lack of such connections is probably the reason for the relatively limited use of precast structural members heretofore. To meet this requirement, I embed lengths of metal pipe in certain of the members such as girders, beams, joists, and the like. The pipe lengths are welded to reinforcing rods embedded in the members, thus imparting the necessary rigidity to the connections. The pipe lengths may also have relatively short metal anchor rods welded thereto for embedding in the members, extending parallel to the longitudinal reinforcing rods therein. By thus welding the reinforcing rods and anchor rods to the pipe lengths, instead of relying on some other form of tie, such as looping the rods around the pipe lengths, I obtain an extremely rigid bond between the pipe lengths and the concrete and avoid any danger of cracking of the concrete adjacent the pipe lengths which would result in breaking the bond therebetween.

The importance of this feature is readily observed from the table of allowable stresses in concrete under shear in terms of percentages of the ultimate compressive strength (Building Regulations for Reinforced Concrete, American Concrete Institute, Detroit, Michigan, 1941) as follows:

	Percent
1. Beams with no web reinforcement and and without special anchorage of longitudinal steel.	
2. Beams with no web reinforcement but with special anchorage of longitudinal steel.	
3. Beams with properly designed web reinforcement but without special anchorage of longitudinal steel.	
4. Beams with properly designed web reinforcement and with special anchorage of longitudinal steel.	

12

Members embodying my invention are in the last

2

of the above groupings and thus have an allowable shear stress several times that of members without anchorage of the longitudinal reinforcing rods.

5 The pipe lengths to which the rods are welded also afford means to position the rods accurately in the forms and maintain them rigidly in position while pouring concrete.

I preferably employ pipe of a convenient size, such as 1 1/2", for embedding in the members to provide the necessary connections. The pipe lengths are preferably positioned in the members so that their centers are substantially 2 1/2" from the nearest surface of the member, thus providing an adequate thickness of concrete to protect the pipe lengths from fire and corrosion.

I have invented a novel type of concrete member having means adapted to form a simple yet permanent and rigid tie between one member and the member or members adjacent thereto. In a preferred embodiment, I provide a precast concrete member with longitudinal reinforcing rods or bars and, adjacent the ends of the member, I embed pipe lengths therein between the bars and weld them thereto. The bores of the pipe lengths are adapted to receive tie means such as a bolt or dowel extending from an adjacent member. The reinforcing bars extend beyond the embedded pipe lengths and terminate closely adjacent the extreme ends of the concrete members. This prevents the concrete adjacent the ends from breaking out under the stress to which the members are subjected when assembled in a building. The bars and pipe lengths, being welded together, constitute a rigid frame or truss which is effective to transmit the load on one member through the reinforcing thereof to a supporting member. In some cases rectangular pipes and ties may be used.

40 Further details and novel features of the invention will become apparent during the following complete description which refers to the accompanying drawing. In the drawing,

45 Figure 1 is a transverse section through a pair of members having precast reinforced concrete splice plates on each side thereof and secured thereto;

50 Figure 2 is a section taken along the plane of line II—II of Figure 1;

55 Figures 3 and 4 are views similar to Figures 1 and 2 showing members and splice plates of larger size;

60 Figure 5 is a vertical section through a column and the ends of a pair of girders supported thereon;

65 Figure 6 is a partial section taken along the plane of line VI—VI of Figure 5;

70 Figure 7 is a view similar to Figure 6 showing a slightly modified splice plate; and

Figure 8 is a partial plan view of a modified form of member.

Referring now in detail to the drawing, and, for the present, to Figures 1 and 2, a precast member 10 of any suitable length has upper and lower longitudinal bars 11 and 12 embedded therein in pairs, one pair being adjacent each side of the member. Stirrups or cross ties 13 extend around the bars at intervals and are welded to them. Pipe lengths 14 are embedded in the member 10 adjacent the ends. As shown in Figure 2, the pipe lengths are transverse to the bars and are welded thereto. The bars are straight throughout their length and the ends extend beyond the pipe lengths 14 to within a short distance of the extreme ends of the members 10, thus adequately reinforcing the concrete at the ends of the member beyond the pipe lengths.

Splice plates 15 are disposed on opposite sides of a pair of the members 10 arranged end to end. The splice plates may be of any suitable length. If the members 10 are 8" x 8", the splice plates are preferably 4" wide and 8" deep. The splice plates have upper and lower longitudinal reinforcing bars 16 and 17 and pipe lengths 18 embedded near the ends hereof, the pipe lengths extending transversely of the bars and welded thereto. The splice plates also have stirrups or cross ties 19 welded to the bars. As in the case of the members 10, the bars 17 extend beyond the pipe lengths 18. The center-to-center spacing of the pipe lengths 18 is such that when the pipe lengths 14 of a pair of members 10 disposed end-to-end are in alignment therewith the ends of the members are in substantial abutment. When the members to be connected end-to-end have been assembled with the splice plates as shown in Figures 1 and 2, tie members such as rivets or bolts 21 may be inserted through the aligned pipe lengths 14 and 18 to secure the splice plates and members firmly together.

Figures 3 and 4 show members 10a and splice plates 15a generally similar to those already described except that each member has intermediate reinforcing bars 22 in addition to the upper bars 11 and lower bars 12. The splice plates also have intermediate bars 23. Stirrups or cross ties 19a extend around the bars 16, 17 and 23. The pipe lengths 14a in the members 10a are disposed transversely of the bars and between adjacent pairs. The pipe lengths and the splice plates are similarly disposed, there being two pipe lengths in each end of each member 10a and in each end of each splice plates. Stirrups or cross ties 13a extend around the bars 11, 12 and 22. When the members and splice plates are assembled they may be permanently secured by rivets or bolts 21a or tie bars may be inserted through the pipe lengths and welded thereto at their ends.

Figure 5 illustrates a column 23' supporting the ends of a pair of girders 24 which are generally similar to the members 10 and 10a. The column has an integral base 25 rested on a field-cast footing 26 with a layer of grout therebetween. Anchor bolts 27 embedded in the footing project upwardly through holes in the base 25 formed by pipe lengths embedded herein and welded to stirrups 29. The column has longitudinal reinforcing bars 30 projecting above the upper end thereof and partially through the pipe lengths 14 embedded in the members 24. The ends of bars 30 may be welded to pipes 14. I may fill the space between bars 30 and pipe lengths 14 with grout. The bars

30 have cross ties welded thereto at intervals similar to the ties 13 and 13a.

The girders 24 differ from the members 10 and 10a in that the ends thereof are notched as at 31 and the ends of the upper reinforcing bars 32 are substantially flush with the extreme ends of the members and thus project somewhat beyond the wall of the notch 31. The abutting bars 32 of adjacent girders are welded as shown at 33, access for the welding means being afforded by the recess formed by the notches 31. The lower reinforcing bars 32a are similar to the bars 12 of the members 10 and 10a and also may be welded at their ends as bars 32 are welded. A further feature of the members 24 is the provision of anchor bars 34 welded to the pipe lengths 14 extending inwardly therefrom and embedded in the concrete.

Figure 6 further shows the arrangement of the girders on the column. Specifically, it shows a 12" wide girder 24 resting on an 8" wide column 23'.

Figure 7 is similar to Figure 6 showing a 16" wide girder 31 resting on a 12" wide column 38. The girder has lower reinforcing bars 39 arranged in pairs, one bar of each pair extending on each side of each of the pipe lengths 14 being welded thereto.

Figure 8 shows a modified form of member 40 having longitudinal reinforcing bars 41 and pipe lengths 42 embedded therein and welded together. The bars are disposed on the outer side only of the pipe lengths, are straight throughout their entire length, and extend beyond the pipe lengths to points closely adjacent the extreme ends of the members. Stirrups 43 extend around the bars 41 and are welded thereto. There are several pairs of pipe lengths at each end of the member as shown in Figure 8. Stirrups 44 extend around the pipe lengths of each pair and are welded thereto.

It will be apparent that the invention provides precast concrete members having means whereby adjacent members in a construction may be easily yet permanently united. The reinforcing bars, being welded to the pipe lengths through which the tie means pass, transmit the load applied to one member directly to the members connected thereto. The ends of the bars projecting beyond the pipe lengths prevent breakage of the concrete at the extreme ends of the members. The connecting means is equally simple and effective in the case of splice plates for uniting members abutting end-to-end as in the case of the column and girder combination in which the ends of the two aligned girders rest on a single column.

Although I have illustrated and described but a few modifications of the invention, it will be recognized that changes in the constructions disclosed may be made without departing from the spirit of the invention or the scope of the appended claims.

I claim:

1. In a building construction a plurality of precast reinforced concrete members, said members including a member having a tie extending therefrom and a second member having a longitudinal reinforcing bar embedded therein and having a metal member closely adjacent an end of said second member transversely disposed adjacent a side of said bar and being welded to it, said metal member having a bore receiving said tie, said second member having another spaced, longitudinal reinforcing bar welded to

said metal member, one of said bars extending beyond said metal member and being welded to a similar bar of another member in an axial position with respect to said second member.

2. A building construction comprising a plurality of precast reinforced concrete members, said members including a member having a tie means extending therefrom and a second member having embedded in the concrete thereof a frame comprising two spaced, longitudinally extending, primary reinforcing bars, said bars being straight for their entire length and having closely adjacent an end transversely disposed between them a metal member, the ends of said bars projecting in a straight line beyond said metal member and terminating in proximity to the end of said second member, said metal member being welded to said two bars and having a bore therein receiving said tie means extending from said first-mentioned member.

3. A building construction comprising a plurality of precast reinforced concrete members, said members including a member having tie means extending therefrom and a second member having embedded therein a frame comprising two straight, spaced, longitudinally extending, reinforcing bars, a pair of transversely extending metal members disposed between said bars closely adjacent one end of said second member, said bars extending beyond said metal members and terminating in proximity to the end of said second member, each metal member being welded to one of said bars and each having a bore therein receiving said tie means extending from said first-mentioned member.

4. A building construction comprising a plurality of precast reinforced concrete members, said members including a member having a tie means extending therefrom and a second member in abutting engagement therewith having embedded in the concrete thereof a frame including two spaced apart, longitudinally extending, reinforcing bars and a metal member having a bore therein disposed transversely between said bars closely adjacent an end of said second member and welded to said bars, the extreme ends of said bars projecting beyond the metal member, said metal member receiving said tie means.

5. A building construction as defined by claim 4 characterized by the portion of said bars projecting beyond the metal member having cross bars welded thereto, thereby reinforcing the extreme end portion of said second member.

6. A building construction comprising a plurality of precast reinforced concrete members, said members including a first member having a tie means extending therefrom and a second member in abutting engagement with said first member and having embedded in the concrete thereof a metal frame composed of two spaced apart, longitudinally extending, reinforcing bars bonded to said concrete, and a metal member having a bore therein disposed transversely between said bars closely adjacent an end thereof and welded to said bars, said metal member receiving said tie means, said tie means serving to transmit from said first member a force acting on said metal member parallel to the longitudinal axis of said second member, and in either direction therealong, the bearing of said metal member on the concrete of said second member being shared between said bars by virtue of the welding of said metal member to said bars and the

bond of the concrete of said second member to said bars.

7. A building construction comprising a plurality of precast reinforced concrete members, 5 said members including a first member having spaced tie means extending therefrom and a second member in abutting engagement therewith having embedded in the concrete thereof a metal frame composed of three spaced-apart, longitudinally extending, reinforcing bars, said bars being equally spaced from a side of said second member and including outer bars and an inner bar, and two metal members each having a bore therein disposed transversely between said bars 10 closely adjacent an end thereof, said two metal members receiving said tie means and being welded to said inner bar and each metal member being welded to one of said outer bars, each metal member being spaced the same distance 15 from one end of said second member, thereby tying the three bars together and preventing lateral movement thereof when said tie means exerts a force parallel to said bars in either direction therealong.

20 8. A precast reinforced concrete structural unit comprising an elongated mass of concrete having embedded therein a metal frame including two spaced-apart, longitudinally extending, reinforcing bars, and a metal member having a bore therein being transversely disposed between said bars closely adjacent an end of each bar, said metal member being welded to at least one 25 of said bars.

9. A precast reinforced concrete structural 30 unit comprising an elongated mass of concrete having embedded therein a metal frame including three spaced-apart, longitudinally extending, reinforcing bars and two metal members each having a bore therein, said metal members being transversely disposed between said bars closely 35 adjacent an end thereof, said bars being equally spaced from a side of said unit and including outer bars and an inner bar, said two metal members being equally spaced from one end of said 40 unit and each metal member being welded to one of the outer bars and to the inner bar.

10. A building construction comprising a plurality of precast reinforced concrete members, 45 said members including a first member having a tie means extending therefrom and a second member in abutting engagement therewith having a compression area and a tension area, two spaced, longitudinal, reinforcing bars being embedded in the tension area of said second member, 50 a metal anchor having a bore therein being embedded in the tension area and in the compression area of said second member, said anchor being disposed transversely to said two bars and welded thereto and being positioned adjacent an end of each of said bars, said tie means in said 55 first member extending into said bore in said anchor.

11. A precast concrete structural unit comprising an elongated mass of concrete having a compression area and a tension area, two spaced, longitudinal, reinforcing bars being embedded in the tension area of said unit, a metal anchor having a bore therein being embedded in the unit and extending into the tension area and the compression area adjacent an end of said unit, said anchor being disposed transversely to and being welded to an end of each bar.

ALBERT HENDERSON.
